UNITED STATES PATENT OFFICE.

PETER FILIPPONE, OF NEWARK, NEW JERSEY.

CONCRETE FLOOR AND CEILING CONSTRUCTION.

1,275,668.

Specification of Letters Patent. Patented Aug. 13, 1918.

Application filed March 7, 1918. Serial No. 220,951.

To all whom it may concern:

Be it known that I, PETER FILIPPONE, a citizen of the United States, and a resident of Newark, county of Essex, and State of New Jersey, have invented certain new and useful Improvements in Concrete Floor and Ceiling Constructions, of which the following is a specification.

In the construction of flat members of concrete, such as floors or the like, the greater portion of the tensile strain comes at or near the bottom or lower surface, while stresses at or near the upper surface are largely of compression. Such construction is therefore customarily made up of girders of suitable depth reinforced with steel bars or the like near the lower part thereof to take the tensile strain off the concrete, such girder members merging into the floor or other flat upper surface of the concrete near the top thereof.

Hollow domes, forms, arches or the like have been provided to fill out the spaces between the girders while the concrete is being put in place and serve as forms for the concrete girders which are formed between them, and temporarily support the concrete of the floor above them. Such arches, domes and the like are sometimes removable and are taken down after the concrete has set, to be again used in other places, and in some cases, particularly when made of material such as sheet steel, they are left permanently in place. In either case, special provision has to be made for securing metal lath, expanded metal or the like underneath the structure to take the plaster for the ceiling, and the work of securing such metal lath or the like in place, and the cost of the metal lath or the like material itself, forms a considerable item in the cost of construction, and at the same time an element of weakness is introduced, since the fastenings for securing the metal lath or other support for the ceiling plaster in place may be insecure, in which case the ceiling formed by plastering thereon will not be properly supported.

The present invention provides a novel type of domes, arches or the like, for the purpose above referred to, which are cheap and simple to construct, are of sufficient strength to bear any strains imposed thereon during construction work, and which become a permanent part of the structure and are firmly embedded or anchored therein, and at the same time the material thereof,

or part of such material, may be used to take the place of the metal lath, expanded metal or the like heretofore separately provided to take the ceiling plaster, whereby the work of preparing for and putting the ceiling in place may be materially reduced and the cost of the ordinary metal lath or other material, heretofore used to take the ceiling plaster, may be entirely saved. Also a saving is effected in such double use of valuable material, such as steel, serving both as a mold for the concrete and as a permanent base for the ceiling plaster, without any reduction in the strength of the finished structure, and in fact additional strength may be secured and there can be no possibility of the ceiling or parts of it getting loose or coming down.

With the foregoing and related objects in view, my invention consists in the steps, processes, elements, combinations and features of construction herein set forth and claimed.

In the accompanying drawings I have shown certain embodiments of my invention, but it is to be understood that the same are for illustration only and that I am not to be limited to such specific form or forms shown.

In said drawings, Figure 1 is a perspective view of one form of dome for use in concrete work. Fig. 2 is a fragmentary, elevational view with parts broken away and showing a series of arches in place in a concrete floor. Fig. 3 is a view generally similar to Fig. 2, but showing domes of slightly modified form with girders running in both directions and showing the reinforcing material of certain of the domes brought down and rearranged to form a support for ceiling plaster. Fig. 4 is a view similar to Fig. 2 but with a modified form of arch, and Fig. 5 is a plan view of a sheet of cardboard or the like used in making one form of dome in accordance with my invention. Fig. 6 is a view of the cardboard after being pressed or otherwise formed in place, and Fig. 7 is a side view of the cardboard member shown in Fig. 6. Fig. 8 is a plan view of a reinforcing member for a dome which may be of material such as wire mesh as shown at the left hand portion of such figure, or may be of other material such as expanded metal as shown in the upper right hand corner thereof. Fig. 9 is a view of the reinforcing portion of a dome in accordance with my invention formed from the blank of Fig. 8 by

pressing or stamping in place. Fig. 10 is a cross-sectional view taken on line 10—10, Fig. 9. Fig. 11 is a perspective view of the parts shown in Figs. 6 and 9 assembled together to form a complete dome member. Fig. 12 is a cross-sectional view on line 12, 12, Fig. 11, and showing the use of expanded metal instead of wire mesh as is shown in Fig. 11, and Fig. 13 is a perspective view of 10 an arch member similar to the dome shown in Fig. 11 but with the omission of the ends.

The hollow member having the form of a dome, arch or the like, of the present invention includes, in general, a metal reinforcing portion which may be of any suitable foraminiferous or reticulated construction, as, for example, mesh formed of wire may be used, or the use of expanded metal may be resorted to. Such material may be 20 in other forms.

A covering is applied to the top of the dome or arch so formed, and such covering preferably extends downward at least part way along the side or sides and ends of the 25 arch or dome and is sufficiently impervious to prevent the passage of water or thin cement mixture through the foraminiferous reinforcing portion of the member. Such covering may be of material such as cardboard, strawboard, pasteboard, or any other form 30 of material which is cheap and light and will serve at least for a time to prevent the passage of thin cement, may be used, the term "cardboard" being hereinafter employed, but being intended as a general designation for materials of the sort referred to. The covering material may be corrugated or otherwise formed or reinforced so as to obtain the greatest strength possible.

40 The reinforcing portion of the hollow arch or dome is exposed at least partially so as to be secured to or embedded in the concrete members as formed, and this result may be obtained in various different ways, 45 as, for example, in the domes and arches of Figs. 1 and 2 the impervious covering extends down but part way on the outside of the metallic portion of the member and the lower part of the latter is exposed directly 50 against the concrete when the latter is put in place, and a water-tight barrier is provided at this portion on the interior of the member which may, however, be later removed when the forms are taken down. In 55 the dome of Fig. 11 and the corresponding arch of Fig. 13 the water-tight outer enveloped of the hollow member is brought down to substantially the bottom of such member, and the reinforcing material is turned outwardly at its lower edge and becomes embedded in the concrete material forming the girder.

60 The reinforcing material of the hollow member at the upper portion thereof being 65 protected from contact with the cement by

a covering interposed between it and the cement, such portion of the reinforcing member is entirely free from the concrete, and when the latter has hardened and the supports have preferably been removed from 70 beneath, such reinforcing member can be pulled down or otherwise re-disposed and arranged at about the ceiling level, whereupon the ceiling plaster can be applied directly thereto.

75 In Fig. 1 the interior reinforcing portion of a dome is shown formed of material such as wire mesh and as indicated by reference numeral 10, and a covering of cardboard or like material 11, preferably corrugated 80 at its edges, is placed thereover and extends downwardly about half way along the sides of the dome member and therebeneath, and on the interior of such member is provided a removable wall for the exclusion of the 85 passage of water or thin cement and represented by the reference numeral 10. The material for the member 12 may be cardboard or the like suitably fastened to the reticulated dome of the wall, or strips of 90 wood may be used, or various other materials.

95 In Fig. 2 arches 13 are illustrated, but the hollow members are otherwise similar to that shown in Fig. 1, the arch form of the 100 reticulated metal portion being illustrated at 10', the covering, preferably of corrugated cardboard, at 11', and the lower water dam or the like arranged at each side being shown at 12'. These members are spaced 105 apart, as indicated at 14, and suitable supporting device, as a false floor 15, is laid apart to receive the domes and affords a temporary support while the construction is being erected. Reinforce members 16 are arranged 110 within the space 14 for the girder and are adapted to take up tensile strains imposed on said girder. The concrete forming the 115 floor and girders is illustrated at 17. At the left hand lower corner of Fig. 2 the reinforcing member 10' is shown brought downward to afford a net-work for the application of the ceiling plaster. As shown, it is turned down at a line indicated by the 120 numeral 18, which is at about the bottom of the downwardly extending side portions of the cover 11', the reinforcing member in the neighborhood marked 19, where it is exposed to the concrete as the structure is formed, being embedded therein, at least to some 125 extent, and firmly secured thereto upon the concrete hardening. Such reinforcing member 10' is shown extending downwardly at 20 and laterally at 21, the portion 21 being that which receives the plaster for the ceiling.

125 In the remaining figures a slightly different form of hollow member is shown, the impervious covering extending in the member shown in these views substantially to the bottom thereof. Figs. 5 to 11 illustrate the 130

various steps which may be carried out in making a complete dome of this type. A sheet 30 of cardboard is cut to the proper size to form a blank and is formed in appropriate forming devices, as by means of dies, for example, a desirable form therefor being illustrated in Fig. 6 in which the top portion 31 is left plane and the side walls 32 are turned down and corrugated, as indicated at 33, 33. The lower edge is preferably also corrugated at 34, 34, Fig. 7.

The reinforcing member is similarly formed. The foraminous metallic blank 40 is illustrated in Fig. 8 made up of any appropriate form and material. Wire mesh is illustrated at 41 for use as such material, and expanded metal at 42, but other forms of reticulated metal may be used. Such material is pressed, stamped or otherwise formed into domes and arches. In Fig. 9 a dome is shown having a flat top portion 43, side members 44 provided with corrugations 45 and bottom corrugations 46, 46 similar to those given the cardboard and illustrated in Fig. 7. Preferably sufficient material is provided in the blank 40 so that a flange or outward extension 47 may be provided extending outwardly and preferably upwardly beyond the side walls, as clearly shown in Fig. 10. The completed dome is shown in Fig. 11, in which the properly formed covering member 30^a is placed over the similarly formed reinforcing member 40^a, leaving the marginal extension 47 projecting therearound.

In Fig. 13 an arch is illustrated and its covering is designated by the reference numeral 30'. The reinforcing member 40' is similar to that of the dome of Fig. 11, but without the ends, and the lateral extensions or flanges 47' extend beyond the arch member and are adapted to be embedded in the concrete. In Fig. 12 a partial cross-sectional view of Fig. 11 is shown, but with expanded metal 48 in place of the wire mesh 40, the outwardly projecting flange of the expanded metal being illustrated at 49.

In Figs. 3 and 4 are shown, respectively, concrete structures embodying the use of domes and arches such as shown in Figs. 11 and 13, and it appears in these figures how the projecting flanges 47, 47' are embedded in the concrete of the girders and firmly anchored thereto. As appears clearly in these views, the domes are preferably made use of when girders running at right angles to one another are to be formed and tensile strain is to be taken in both directions by the reinforcing rods or bars 16, whereas the arch members are placed adjacent to one another, and with their use a floor structure is obtained having girders and reinforcing bars 16 running in one direction only.

In Fig. 3 a hook 50 is illustrated as ap-

plied to the reinforcing material 40 to pull the same down after the concrete is set and the forms are removed, and rearrange it in proper position and location to receive and afford an anchoring for the ceiling plaster. 70 It will be noted, however, that somewhat more difficulty may be encountered in properly re-arranging such material than in the case of Fig. 2, in which the lower side portion of the reinforcing material is embedded 75 in and secured firmly to the concrete of the girder and affords a turning line 20 along which the material can be turned down and below which it is directly received and supported in the concrete of the girder. It is 80 quite feasible, however, to make such re-arrangement in the construction shown in Figs. 3 and 4 with only perhaps some slight additional difficulties of manipulation, and in either case it will be seen that the ceiling 85 plaster is applied to retaining material as wire mesh, expanded metal or the like, firmly and permanently embedded in the hardened concrete so that after the ceiling 90 plaster has been applied there is no possibility of the reinforcing material, to which it is applied, getting loose or parting from the concrete and ruining the ceiling.

It will be understood that the embodiments illustrated are intended only for affording a clear understanding of my invention and not for purposes of limitation, and that changes may be resorted to within the scope of my claims and without departing 95 from my invention or sacrificing any of its 100 advantages.

I claim:

1. A mold member for concrete floor construction comprising top and side walls of foraminous metallic material, and an outer covering of light substantially impervious material extending over the top and at least part way down on the sides. 105

2. A mold member for concrete floor construction comprising top and side walls of foraminous metallic material, and an outer covering of light substantially impervious material extending only part way down upon the sides of the metallic material and leaving 110 the lower portion exposed to come in contact with and be embedded in the concrete. 115

3. A hollow mold member for hollow domed concrete floor construction comprising a hollow shell of foraminous metallic material, and a covering of substantially impervious material extending only part way over the sides of the metallic material, whereby concrete may come directly in contact with and be keyed to the exposed portion of such foraminous metallic material. 120

4. A hollow mold member for hollow domed concrete floor construction comprising a shell of foraminous metallic material, a substantially impervious cover therefor extending part way over the sides thereof, and 125 130

a substantially impervious lining for the remainder of the sides thereof.

5. A concrete floor having a plurality of downwardly directed recesses formed in its lower portion, the walls and the surfaces thereof about and at the upper parts of said recesses being formed substantially entirely of concrete, sections of foraminous metallic material permanently embedded in the concrete about the margins of the recesses and having portions thereof which have served as molds for forming the recess extending across the mouths of the recesses, and plastic material beneath the floor and keyed in said foraminous material.

6. The process which includes providing inverted hollow members of foraminous metallic material having a covering of material substantially impervious to concrete, arranging such members with spaces between them and with at least a part of their foraminous material exposed, putting concrete in the spaces between and over the members to form a floor with girders, permitting the concrete to set and harden, whereby the exposed portions of the members are permanently secured to the concrete, and deforming the covered parts of the members by bending to adapt them to take surface plaster, and applying plastic material thereto.

7. The process of making concrete structures having hollow interior spaces therein which comprises the provision of a mold comprising deformable foraminous material covered in part with substantially impervious material, putting concrete in place about

such mold and permitting it to set, whereby uncovered portions of the foraminous material are permanently secured to the concrete, and deforming the foraminous material to leave a space between it and the concrete.

8. The process of making concrete structures having hollow interior spaces therein which comprises the provision of a mold comprising deformable foraminous material covered in part with substantially impervious material, putting concrete in place about such mold and permitting it to set, whereby uncovered portions of the foraminous material are permanently secured to the concrete, deforming the foraminous material to leave a space between it and the concrete, and applying cementitious material to the deformed foraminous material.

9. The process of constructing concrete floors which comprises the provision of a mold comprising deformable foraminous material covered in part with substantially impervious material, putting concrete in place about such mold and permitting it to set, whereby uncovered portions of the foraminous material are permanently secured to the concrete and deforming the foraminous material by pulling it downwardly, leaving a hollow space above it, and applying cementitious material to the deformed foraminous material to form a ceiling beneath the floor.

In testimony that I claim the foregoing, I have hereto set my hand, this 5th day of March, 1918.

PETER FILIPPONE.
